UNITED STATES PATENT OFFICE.

HARRY H. KELLEY, OF ATLANTA, GEORGIA.

PICK-MOTION FOR LOOMS.

1,172,144.

Specification of Letters Patent. Patented Feb. 15, 1916.

Application filed October 8, 1914. Serial No. 865,717.

To all whom it may concern:

Be it known that I, HARRY H. KELLEY, citizen of the United States, residing at Atlanta, in the county of Fulton and State 5 of Georgia, have invented certain new and useful Improvements in Pick-Motions for Looms; and I do hereby declare the following to be a full, clear, and exact description of the invention, such as will enable others 10 skilled in the art to which it appertains to make and use the same, reference being had to the accompanying drawings, and to letters or figures of reference marked thereon, which form a part of this specification.

15 My invention relates to improvements in pick motion for looms.

The object of the invention is to provide improved means for operating a picker stick, so as to cause the picker stick to travel in a 20 horizontal line to make a more effective blow and to insure a quick action of the parts.

The invention also comprehends improvements in the construction and arrangement of parts, which will be hereinafter described 25 and particularly pointed out in the claims.

In the accompanying drawings: Figure 1 is a side elevation of my improved pick motion, the parts being shown in an intermediate position. Fig. 2 is a face view of 30 the latter. Figs. 3 and 4 are diagrammatic views, illustrating the movement of the pick motion.

1 indicates the frame of a loom; 2, a plate or support secured thereto, and from this 35 plate extends a shaft 3, fastened in position by a nut 4. Freely mounted on the shaft 3 is a sprocket wheel 5, around which passes a chain 6, operated from any convenient part of the loom mechanism. On the outer 40 face of the hub of the sprocket wheel is a cam 7, having an abrupt edge 8. Slidably mounted on the shaft 3 is a sleeve 9, closed at its outer end and provided on its inner edge with a cam 10, formed with an abrupt 45 edge 11, the cam surface and the abrupt edge corresponding with the cam surface 7 and edge 8 on the hub of the sprocket wheel. Near the closed outer end of the sleeve 9 are two openings 12 and 13, and fitting in 50 the opening 13 is a cock 14, for regulating the exit of air, as will be presently explained.

Depending from the sleeve are lugs 15 and fitting between same and pivotally 55 mounted on a pin 16 is a link 17. The lower

end of link 17 is pivoted to an arm 18, as at 19, the inner end of said arm being pivoted at 20^a to lugs 20, extending from the lower end of plate 2. The outer end of arm 18 projects beyond the link 17 and pivoted 60 thereto as at 22, is the lower end of a picker stick 23. The picker stick is mounted in a casting which is formed with an opening to straddle the sleeve 9. Extending up from the sleeve 9 and diametrically disposed to 65 lugs 15 are lugs 24, and pivoted between said lugs at 25 is a horizontal link 26, the outer end of the latter being pivoted at 27 to the picker stick.

Suitably supported on the inside of frame 70 1, is a yoke 28 formed with an opening 29. Pivoted to the picker stick at 30 is one end 75 of a spring 31, the inner end of which is threaded and is passed through the opening in the yoke, the end of said spring being threaded and a nut 33 applied, whereby to adjust the tension of the spring.

In operation, when the sprocket wheel 5 is rotated in direction of the arrow *a*, shown in Fig. 2, the cam 7 will act on the cam 10 80 and force the sleeve out. While the sleeve is being moved out, air is drawn through the opening 12, which subsequently acts as a cushion, when the parts are returned to normal position. In the outward movement of 85 the sleeve, the picker stick rocks on the pivot 22, and because of the arm 18 and links 17, and 26, the upper end of the picker stick travels in a horizontal line, as indicated by the dotted lines in Figs. 3 and 4. As the 90 pivot 16 of link 17 moves with the sleeve 9, in a horizontal line, and because the arm 18 to which the said link is pivoted, is mounted to rock on a fixed part of the frame, said sleeve imparts to pivot 19, consequently to the lower end of the picker stick, a slight vertical motion. The length of the link 17 and the distance between pins 19 and 22 is so proportioned that the vertical motion of pin 22 is equal to the rise of 95 the arc described by the upper end of the picker stick, thus causing the latter end of said picker stick to travel in a straight line. In the revolution of the sprocket wheel, the cams will throw the picker stick to the position shown in Fig. 3. When the edges 8 and 11 of said cams pass each other, the spring 31 will immediately act to draw the picker stick back to normal position, as 100 shown in Fig. 4. When the sleeve 9 is 105

110

moved toward its normal position, air trapped between the closed end of the sleeve and the outer end of the shaft acts to relieve the stick, the air gradually escaping through opening 12 and cock 14. After the 5 opening 12 passes the end of the shaft 3, the air confined between the end of the sleeve and the end of the shaft acts as a cushion to allow of the more gradual meshing of the cam surfaces, the air so confined being forced 10 out through the cock 14.

From the foregoing description it will be seen that the link 17 carries the weight 15 of the picker stick 23 and the arm 18, the latter therefore being of the floating type. The link 26 acts to transmit the motion of the sleeve 9 to the picker stick, which with the aforesaid link 17 and arm 18 imparts movement to the picker stick, whereby the 20 upper end will travel in a horizontal path, as stated.

What I claim is:

1. In a pick motion for looms, the combination of a shaft, a cam on the shaft, a 25 sleeve mounted to slide on the shaft, said sleeve having a cam with which the aforesaid cam coöperates, a picker stick, a support, an arm pivoted to the picker stick and pivotally mounted at its opposite end to the 30 support, a link pivoted to the sleeve and the arm, a second link pivoted to the picker stick and the sleeve, whereby when the cams move the sleeve the upper end of the picker stick will travel in a horizontal path, and 35 means for retracting the sleeve and with it the picker stick after operation of the cams.

2. A pick motion for looms, comprising a shaft, a rotating cam mounted on the shaft, a sleeve slidably mounted on the shaft and 40 operated in one direction by the cam, a picker stick, means including an arm and links, and a spring for operating said sleeve with said picker stick to cause the upper end of the latter to travel in a horizontal path, 45 and a pneumatic cushion to absorb the shock when the sleeve is operated.

3. A pick motion for looms comprising a support, a shaft extending outwardly therefrom, a rotating cam mounted on the shaft, 50 a sleeve mounted on the shaft and having a cam surface with which the first mentioned cam coöperates, said sleeve having openings, there being a chamber formed between the ends of the shaft and the sleeve 55 and with which the openings communicate, whereby to form a cushion for the sleeve, a picker stick, an arm pivoted to the picker stick and the support, a link connecting the arm and the sleeve, a second link pivoted to 60 the sleeve and to the picker stick, whereby to cause the upper end of the picker stick to move in a horizontal path.

4. In a pick motion for looms, the combination of a slidable sleeve, means for sliding 65 the sleeve in one direction, a support, a

picker stick, an arm pivoted to the support and to the lower portion of the picker stick, a link pivotally connected to the sleeve and to the picker stick above the pivotal point of the arm, means for moving the picker stick in the reverse direction, and means for cushioning the picker stick when it is returned to normal position. 70

5. A pick motion for looms comprising a frame, a picker stick, means for moving the 75 picker stick in one direction including a cam, a sliding element actuated by the cam, and links between the frame, picker stick and sliding element, said cam, sliding element and links causing the lower end of 80 the picker stick to move in the arc of a circle and the upper end of the said picker stick to move in a straight line, and means independent of the cam for quickly reversing the movement of the picker stick. 85

6. A pick motion for looms comprising a frame, a picker stick and means including a cam, a sliding sleeve, and connections between the frame, picker stick and sliding sleeve for moving the picker stick in one direction to cause its lower end to move in the arc of a circle and its upper end to move in a straight line, and means for quickly reversing the picker stick in the heretofore described path. 90

7. A pick motion for looms comprising a picker stick, means for moving the picker stick in one direction including a positively driven sliding element and links which cause the lower end of the picker stick to move in a curved path and its upper end to move in a straight line, means for quickly reversing the said movement of said picker stick, and a pneumatic cushion to absorb the shock of the movement of the picker stick. 100

8. A pick motion for looms comprising a picker stick, means for mounting the picker stick so that when said picker stick is moved in one direction its upper end will travel in a straight line and said mounting will rock 110 and cause the lower end of said picker stick to travel in the arc of a circle, a sliding element for supporting said mounting, a cam directly engaging the sliding element to operate same in one direction, and means for quickly reversing the picker stick. 115

9. A pick motion for looms comprising a reciprocating picker stick, a sliding element having a cam surface, a cam engaging said cam surface to operate the sliding element in one direction, links for supporting the lower end of the picker stick, said links being moved by the sliding element whereby when the cam operates the sliding element the operative end of the picker stick is 120 caused to travel in a straight line in one path of its reciprocation, and means for returning the parts to normal position when the cam is disengaged from the cam surface 125 on the sliding element. 130

10. A pick motion for looms comprising a reciprocating picker stick, a sliding element, links coöoperating with the picker stick and the sliding element to cause its upper end to travel in a straight line, a cam acting directly on the sliding element to move same in one direction of its movement, and means for causing the sliding element to quickly travel in its other path of move-

ment when the cam is disengaged there- 10 from.

In testimony whereof I have signed my name to this specification in the presence of two subscribing witnesses.

HARRY H. KELLEY.
